UNITED STATES PATENT OFFICE.

ALLEN O. HANEY, OF LIGONIER, INDIANA, ASSIGNOR TO HANEY GAS ENGINE COMPANY, OF LIGONIER, INDIANA.

PROCESS FOR CAUSING SELF-IGNITION IN EXPLOSIVE-ENGINES.

940,872.

Specification of Letters Patent. Patented Nov. 23, 1909.

No Drawing.

Application filed July 13, 1908. Serial No. 443,297.

To all whom it may concern:

Be it known that I, ALLEN O. HANEY, a citizen of the United States, residing at Ligonier, in the county of Noble, in the State of Indiana, have invented certain new and useful Improvements in Processes for Causing Self-Ignition in Explosive-Engines; and I do hereby declare that the following is a full, clear, and exact description of the invention, which will enable others skilled in the art to which it appertains to make and use the same, reference being had to the accompanying drawings, which form part of this specification.

15 My invention relates to improvements in the process or method of causing self-ignition in explosive engines adapted to avoid the employment of sparking means, high compression, hot tubes, or other adjacent hot surfaces, or an igniting flame.

It is well known that heretofore to produce self-ignition in explosive engines it has been necessary to subject the explosive mixture to a high degree of compression in the explosive chamber or in an auxiliary chamber; or to introduce the explosive mixture into the explosive chamber and then commingle it with air or a very weak mixture previously subjected to high compression in such chamber; or to employ hot tubes; or to charge the mixture with a high degree of heat energy by contact with the highly heated walls of the working chamber, or other adjacent heated surfaces; or it has been necessary to make a combination of the hot surface and a moderate compression.

The primary object of my present invention is to provide a process of causing self-ignition in explosive engines under a low compression of the explosive mixture without the necessity of energizing the same by contact with or proximity to highly heated surfaces of any kind.

40 My invention consists of the process or method of producing self-ignition of the explosive mixture by so utilizing a portion of the heat energy of the products of combustion as to cause an explosion thereof under a low compression.

45 50 Instead of depending solely or in part upon either a high compression of the explosive mixture, or upon the highly heated walls of the explosive chamber or other adjacent surfaces, I retain in the explosion

chamber a sufficient portion, preferably approximately one-half, of the products of combustion at each exhaust therefrom, which residue is then mixed with the fuel to raise the temperature of each freshly admitted charge of fuel after the initial ignition to a point which will self-ignite under a low compression thereof.

55 By the employment of my improved process the initial ignition in an explosive engine is produced by a match or any other suitable external means, after which the engine is self-igniting under a compression pressure which may be varied from 51 pounds upward, whether the walls of the cylinder are hot or cold.

60 65 70 It is found in practice that where a throttle governor is used, and an explosion is missed self-ignition will cease, until another initial ignition is produced as before, because upon the missing of such explosion 75 the exhaust gases are ejected from the working cylinder, leaving no residue thereof to be mixed with the next incoming charge.

75 80 85 In the employment of my process the ignition occurs at the same time regardless and independent of how much variation there may be in the richness of the explosive mixture, the temperature of the pistons or the cylinder walls, the amount of compression, or the initial temperature of the charge. It is thus evident that by the employment of my improved process I eliminate completely the usual difficulties arising from the use of ignition devices, and I am able to secure good thermal efficiency by a low compression pressure in the working chamber, and at the same time maintain a low temperature of the cylinder walls and pistons under all conditions of service.

90 95 The employment of my process also enables the operator to utilize the greater portion of the exhaust gases, and to maintain a low temperature of such gases at the exhaust thereof.

Having thus described my invention and the manner of employing the same what I desire to secure by Letters Patent is:

100 105 110 1. The herein described process of producing self-ignition in explosive engines, by retaining a portion of the products of combustion at each exhaust thereof, then mixing a fresh charge of the explosive mixture with such residue in the explosion chamber,

and then subjecting the same to a low compression in the piston chamber.

2. The process of producing self ignition in low compression explosive engines, which consists in commingling in the explosive chamber a portion of the products of the combustion therein with each successive charge of the working mixture after each exhaust, and then subjecting the mixture to a low compression in the said chamber.

3. The method or process of producing self-ignition in explosive engines which consists in energizing each incoming charge of the explosive mixture by mixing therewith in the combustion chamber a portion of the

products of combustion, and then subjecting the same to a suitable compression.

4. The process of producing self-ignition in explosive engines, consisting in commingling with each incoming charge of the explosive mixture, a proper quantity of the products of combustion after each exhaust thereof, and then subjecting the same to a compression in the explosion chamber.

Signed by me at Ligonier, Noble county, 25 State of Indiana, this 9th day of July, 1908.

ALLEN O. HANEY.

Witnesses:

WILLIAM H. WIGTON,
C. A. WOODRUFF.
